UNITED STATES PATENT OFFICE.

CHARLES D. REEVE, OF GRAND RAPIDS, MICHIGAN, ASSIGNOR TO THE GRAND RAPIDS BRASS COMPANY, OF GRAND RAPIDS, MICHIGAN.

DEVICE FOR FASTENING FURNITURE-TRIMMINGS.

SPECIFICATION forming part of Letters Patent No. 769,184, dated September 6, 1904.

Application filed December 31, 1903. Serial No. 187,339. (No model.)

To all whom it may concern:

Be it known that I, CHARLES D. REEVE, a citizen of the United States, residing at Grand Rapids, in the county of Kent and State of Michigan, have invented a new and useful Device for Fastening Furniture-Trimmings, of which the following is a specification.

This invention relates to devices of that class employed for the fastening of furniture-trimmings, particularly drawer-pulls, knobs, and other devices which are in constant use and which frequently are disengaged by reason of the loosening of the screws or nuts usually employed for securing them in place.

15 A further object of the invention is to provide a novel form of fastening-screw which comprises in an integral structure a threaded shank for engagement with the furniture-trimmings, a tool-engaging portion, and a radially-extending arm having a terminal tooth to be driven into the surface of the wood after the screw has been turned home.

With these and other objects in view, as will more fully hereinafter appear, the invention consists of the novel construction and arrangement of parts hereinafter fully described, illustrated in the accompanying drawings, and particularly pointed out in the appended claim, it being understood that various changes in the form, proportions, size, and minor details of the structure may be made without departing from the spirit or sacrificing any of the advantages of the invention.

35 In the accompanying drawings, Figure 1 is a sectional plan view of a portion of a drawer or other article provided with a furniture-fastening device constructed in accordance with the invention. Fig. 2 is an elevation of the securing-screw as manufactured and placed on the market. Fig. 3 is a plan view of the same.

Similar numerals of reference are employed to illustrate corresponding parts throughout the several figures of the drawings.

In securing drawer-pulls, knobs, and similar furniture-trimmings in place it is usual to employ small bolts and nuts which frequently become loosened from constant use, and the

knobs and pulls are disengaged and lead to much inconvenience in using the furniture.

In carrying out the present invention it is designed to employ a fastening device which when once placed in position may be permanently secured, so that it will be impossible for the trimming to become loosened as a result of any ordinary wear.

In the drawings, 1 indicates the front of a drawer, door, or other article to which a furniture-trimming is to be applied, and in the present instance there is shown a portion of the drawer-pull 2, including a knob or head 3, having a shank portion 4, which extends through the opening in the front of the drawer, and the shank of the knob is provided with a threaded opening for the reception of a screw 5, having a slotted head 6 to be engaged by a screw-driver. One side of the head is extended on tangential lines, which gradually converge and form a tooth or spur 7 at a point somewhat beyond the body portion of the head. This tooth or spur is bent outward, as indicated in Fig. 2, so that the point shall be in a plane beyond the inner surface of the head or that surface which engages with the inner face of the door or drawer, so that the screw may be turned home tight without danger of the spur scratching or otherwise marring the surface. The screw as manufactured and placed on the market is of the character shown in Figs. 2 and 3, and after being turned home tight a single blow of a hammer or other implement will force the spur downward into engagement with the surface of the wood to a position shown in Fig. 1, the screw entering the wood to an extent sufficient to prevent the turning of the screw, while the furniture-trimming is prevented from turning in any suitable manner, as in the case of a drawer-pull by the handle connection 2. When it becomes necessary to remove the furniture-trimming, as where the furniture is to be packed or stored, the spur is readily disengaged by bending it upward, a screw-driver or other similar tool being used for the purpose, and the screw may then be loosened and removed. Screws of this character may be made in large quantities at

a cost but little, if any, greater than the ordinary screws, and as it forms an integral structure there is no necessity of employing locking-washers or other auxiliary fastenings, 5 which not only add to the expense, but require additional time in placing and fastening them in position.

Having thus described the invention, what is claimed is—

- 10 o The combination with a furniture-trimming having an internally-threaded shank portion, of a securing-screw provided with a head portion shaped for engagement by a tool, said

head having an integral radially-projecting arm provided with a terminal tooth or spur, 15 the pointed end of which is in a plane beyond the plane of the inner surface of the head thereby to permit the turning of the screw.

In testimony that I claim the foregoing as my own I have hereto affixed my signature in 20 the presence of two witnesses.

CHARLES D. REEVE.
